(57) **CLAIM**

We claim the ornamental design for an electrical charge storage component, as shown and described.

DESCRIPTION

FIG. 1 is a front side view of the electrical charge storage component;

FIG. 2 is a left side view thereof;

FIG. 3 is a right side view thereof;

FIG. 4 is a top side view thereof;

FIG. 5 is a bottom side view thereof;

FIG. 6 is a rear side view thereof; and,

FIG. 7 is a front, right, top isometric view thereof.

The broken lines in the drawings are for illustrative purposes only and form no part of the claimed design.

The broken line(s) which define the bounds of the claimed design form no part thereof.
